EYE PROTECTIVE SPECTACLE FRAME

Frank W. Lindblom, Warwick, R.I., assignor to Welsh Manufacturing Company, a corporation of Rhode Island

Application May 18, 1959, Serial No. 55,935

Term of patent 14 years

(Cl. D57—1)

FIG. 1

FIG. 2

FIG. 3

Fig. 1 is a front perspective view of an eye protective spectacle frame showing my new design;

Fig. 2 is a rear elevational view; and

Fig. 3 is an enlarged fragmentary detail view thereof.

The dominant features of my design reside in the spectacle frame shown in full lines, characterized by the end portions thereof having the configurations as shown.

I claim:

The ornamental design for an eye protective spectacle frame, substantially as shown and described.
